CANDLE HOLDER

Richard A. Schultz, Kansas City, Mo., assignor to Hallmark Cards, Incorporated, Kansas City, Mo.

Filed Oct. 17, 1972, Ser. No. 300,397

Term of patent 14 years

Int. Cl. D26—01

U.S. Cl. D48—2

Fig. 1.

Fig. 2.

FIG. 1 is a side elevational view of a candle holder, showing my new design; and

FIG. 2 is a central sectional view thereof.

The perforations are partially shown in FIGS. 1 and 2 for convenience of illustration, it being understood that they are uniformly continuous over the areas indicated.

I claim:

The ornamental design for a candle holder, as shown and described.
